UNITED STATES PATENT OFFICE.

HANS E. GRABAU, OF WEEHAWKEN, NEW JERSEY.

MEANS FOR GENERATING HEAT.

No. 901,338.

Specification of Letters Patent.

Patented Oct. 20, 1908.

Application filed June 4, 1907. Serial No. 377,156.

To all whom it may concern:

Be it known that I, HANS E. GRABAU, a citizen of the United States, residing in Weehawken, in the county of Hudson and State of New Jersey, have invented a certain new and useful Means for Generating Heat, of which the following is a specification.

This invention comprises means for generating heat, the apparatus being adapted for use in connection with a variety of appliances and structures, among which may be mentioned soldering irons, sad irons, gas heaters, gas torches, and many kinds of portable tools, as well as in apparatus generally.

The objects of this invention are to rapidly generate and maintain an intense heat which is adapted to be utilized in various ways, such as for heating a portable tool or any form of apparatus, to secure economy in the consumption of the fuel, and to simplify the construction so as to produce a compact device which is economical to manufacture.

Broadly stated, the invention consists in means for generating a vapor under pressure, such as steam, utilizing the pressure of the vapor for entraining air, thus producing a mixture of air and vapor, entraining a mixture of combustible gas or vapor and air by the action of the aforesaid mixture of vapor and air, whereby the two mixtures are combined, and igniting the resulting mixtures for the production of an intense heat by the consumption of a low pressure of fuel (gas).

The invention further contemplates an injector burner embodying in its construction a Bunsen device adapted to supply a mixture of air and gas to a combining chamber into which the aforesaid mixture of gas and air is drawn by the rapid jet of mixture of atmospheric air and superheated steam, whereby the two gaseous vapors are combined and consumed for producing heat of a high temperature.

The Bunsen device affords a convenient means for initially heating the generator and other parts of the apparatus, and, also supplies a combustible vapor from a convenient source of supply and in a form adapted to be united readily with another vapor of economical production, thus utilizing a well-known gaseous fuel which is supplied at a low cost.

Another part of the invention is a vapor

generator which is supplied with a small quantity of liquid, preferably water, whereby said generator, when heated to a high temperature is adapted to produce dry superheated steam, the pressure of which is utilized in a twofold capacity, as a medium for entraining air and producing a forcible air jet which aids in increasing the flow supplied by the Bunsen device and combining with its gases a vapor composed of steam and air.

Another part of the invention is means for feeding a liquid in a small quantity continuously to the generator, whereby intermittent vaporization of the liquid is obviated, and, further, in a novel appliance for regulating the liquid supply in a minute quantity to the generator.

In the accompanying drawings, I have illustrated different practical embodiments of the invention, but the constructions shown therein are to be understood as illustrative only, and not as defining the limits of the invention.

Figure 1 is a vertical section taken longitudinally through an apparatus of my invention, the plane of the section being indicated by the dotted line 1—1 of Fig. 2 looking in the direction of the arrow. Fig. 2 is a horizontal section on the line 2—2 of Fig. 1. Fig. 3 is a vertical cross section on the line 3—3 of Fig. 1 looking in the direction of the arrow. Fig. 4 is a vertical longitudinal section through another embodiment of the invention. Fig. 5 is a vertical cross section on the line 5—5 of Fig. 4.

In the embodiment of the invention shown in the several figures of the drawings, the apparatus is shown as having a casing containing a mixing chamber, A, a Bunsen device, B, for feeding air and gas to said chamber, a vapor generator C, an injector nozzle, D, connected with said generator, C, an injector, E, adapted to extend into the mixing chamber and disposed in alinement with the injector nozzle, D, and means indicated at F and consisting of a tube and control device for supplying liquid to said generator, C. Said drawings represent, further, a compact construction of that form of apparatus which may be appropriately designated as an injector burner, the same being adapted for use in connection with portable tools, such as soldering irons and gas torches. The mixing chamber, A, is formed, prefer-

ably, by a tube which is open at one end and is closed at its other end by a head, a , the latter being provided with a threaded opening, a' , into which is screwed a male threaded end of the injector tube, E. The tubular body, A, of the injector burner is provided with an extension, A', which is shown as being screwed on the closed rear part of the body, and this extension is provided with 10 openings, a^2 a^3 , by which atmospheric air is free to enter the chamber of said extension.

The injector nozzle, D, extends into the chamber of the extension, A', and it is in axial alinement with the injector tube, E. 5 This injector nozzle is integral with or attached to a pipe, d, which is connected at one end with the generator, C, whereby a vapor under pressure, such as dry superheated steam, may be supplied from the generator 15 to the injector nozzle. As shown, the pipe, d, extends alongside of the chambered body, A, so as to occupy a compact relation thereto, and one end of this pipe is attached directly to the generator, C, while the other 20 end of said pipe has an elbow, d', adapted to connect with the injector nozzle. The steam or other vapor is discharged under pressure and with considerable velocity from the nozzle, D, across the chamber of the extension, A', and into the injector tube, E, whereby the jet of steam or vapor entrains atmospheric air through the openings a^2 , a^3 , into the injector tube, E, so that the air and steam are intimately mixed and supplied 25 under pressure into the mixing chamber, A.

The generator, C, may be of any suitable or preferred construction, but as shown in Figs. 1, 2 and 3 of the drawings, said generator is a hollow casting attached to or supported on the tubular body forming the mixing chamber, A. The generator has a chamber, c, into which a liquid is to be admitted, and said generator is provided, furthermore, with a central opening, c', which is opposite 40 to the open end of the mixing chamber, A. Across said open end of this chamber is a gauze diaphragm, G, constituting the flame surface of the injector burner. Said diaphragm is composed, preferably, of a durable metallic gauze which will withstand the 45 effect of the intense heat generated by the burner, and said diaphragm is, practically, between the end portion of the tubular body and the casting forming the generator, C, of 50 Figs. 1 to 3 inclusive.

The Bunsen device is shown as consisting of an extension, b, of the casing inclosing the mixing chamber, A, a casing, b', a supply pipe, b², through which a fixed gaseous 55 fuel under pressure passes, and a nozzle, b³, from which the jet of the fuel passes. The extension b, is at an angle to the axis of the tubular body, and it opens into or communicates with the mixing chamber, A. 60 The casing b', is screwed on the extension, b,

and the supply pipe b², for the purpose of mechanically connecting said parts, and this casing is provided with openings, b⁴, for the admission of atmospheric air to the extension, b. The jet nozzle, b³, is attached to the 70 feed pipe, b², and it extends into the chamber of the coupling, b', as shown in Figs. 1 and 4. The pipe, b², is adapted to be connected in any suitable or usual way with a source of supply of gas or other fuel in a 75 vaporized state, such as a street main, and when the gas is admitted to the pipe, b², it is caused to issue under pressure, and with considerable velocity from the nozzle, b³, whereby the jet of gas entrains atmospheric 80 air through the openings, b⁴. The mixture of air and gas takes place in the extension, b, of the Bunsen device, and it is supplied to the mixing chamber, A. In this connection it is to be observed they may be ignited at 85 the gauze diaphragm, G. Furthermore, the pressure and velocity of the steam issuing from the nozzle, D, is utilized to entrain air through the openings, a^2 , a^3 , so that a mixture of steam and air is secured in the injector tube, E, and injected into the chamber A and, further, the pressure and velocity of the mixture of steam and air issuing from the injector tube increases the fuel supply to 90 the bunsen and aids to carry the combustible mixture of gas and air into the mixing chamber, A, from the bunsen, B.

The two mixtures, one of which is composed of steam and air, and the other of gas and air, are intimately commingled and 100 heated in the mixing chamber, A, and when ignited produce a large volume of heat adapted to be utilized for heating portable tools and other apparatus, the burner being maintained continuously in operation with a 105 relatively small volume of gas, thereby effecting economy in the operation.

It is desirable to feed the liquid continuously to said generator C in order to avoid 110 intermittent vaporization of the liquid, whereby the injector is made to operate continuously for the purpose of keeping the burner in operation and obviating the possibility of cooling off the generator.

Various mechanical devices may be employed for feeding a small quantity of liquid 115 continuously to the generator, but I have found the construction shown in Fig. 2 to be particularly serviceable. This feed mechanism consists of a tube, f, coupled at one end to the generator, C, and arranged in compact relation to the tubular body forming the mixing chamber, A. This supply tube, f, is provided with a nipple, f', which is interiorly screw threaded, and to this nipple is attached a tube or hose, f², adapted to lead from any suitable series of liquid supply. The nipple, f', constitutes a seat for a 120 regulating valve, F', which is shown in the form of a male threaded plug having one 125 130

side cut away at an angle, one end of said plug being enlarged and notched for the reception of a suitable tool, such as a screw driver, for adjusting the valve. Within the 5 tube, *f*, is arranged a rod or wire, *F'*, which extends lengthwise of the tube, as shown in Figs. 2 and 3, said wire or rod operating to reduce the cross sectional area of the passage through said tube, *f*, whereby the liquid is 10 contained in a thin film which extends continuously from the valve, *F'*, to the delivery end of the tube, *f*. The liquid is supplied under pressure or head to the tube, *f*, and the volume admitted to said tube may be increased or decreased by adjusting the valve, 15 *F'*, for the purpose of regulating the area of the port by which the liquid is admitted from the tube or hose, *f'*, to the tube, *f*, and thence to the generator, *C*.

20 In the construction shown, it is preferred to connect the pipes, *d*, *f*, to the tubular body of the injector burner by bands, *g*, which embrace the body and the tubes, thereby binding the parts firmly together, although 25 other means may be employed for uniting the several parts in a substantial way.

The construction shown in Figs. 4 and 5 of the drawings embraces substantially the same elements as the burner shown in Figs. 30 1, 2 and 3 and heretofore described, except that the parts are modified in non-essential particulars. The casing inclosing the mixing chamber, *A*, contains the diaphragm, *G*, and is provided with the extension, *A'*, and 35 the inclined extension, *b*. Within this chamber is the injector tube, *E*, which is attached to the head, *a*. The generator, *C'*, is in the form of a coil of pipe arranged beyond but close to the open end of the mixing chamber 40 and the diaphragm, *G*. Liquid is supplied to said generator by a pipe, *h*, from a tank, *h'*, adapted to contain water. Said pipe has a regulating cock or valve, *i*, of any preferred construction, and in the pipe is a packing of 45 fibrous material indicated at *j*. The aforesaid packing may be composed of any suitable material, such as asbestos fiber, through which the liquid, such as water, is permitted to percolate. The quantity of liquid supplied to the generator, *C'*, is regulated or 50 controlled with a view to feeding a small quantity within the capacity of the generator to convert into vapor. It may be stated that the liquid feed devices which I prefer 55 to employ operate substantially, on the principle of capillary attraction. From the generator, *C'*, extends a tube, *d*, which leads to an injector nozzle, *D'*, the latter being supported in one end of the extension, *A'*, so as 60 to lie in axial alinement with the injector tube, *E*. It is preferred to employ a jet nozzle, *D'*, which is externally threaded in order to mount it in the extension *A'*, said nozzle being, also, screw threaded interiorly 65 for a part of its length. In the female

threaded part of the nozzle is screwed a regulating valve, *H*, which is provided with a stem, *h*, adapted to extend across the port between the vapor tube, *d*, and the passage through the jet nozzle, whereby the valve is 70 adapted to be adjusted for regulating the volume of steam which passes through the nozzle *D'*. The extension, *A'*, is provided with the air inlets, *a'*, and the steam issuing from the jet nozzle entrains air through these 75 openings into the injector tube, *E*, in a manner heretofore described. The bunsen, *B*, of Fig. 4 is shown as having the casing, *b'*, integral with the inclined extension, *b*, and the feed tube, *b*, is integral with the jet 80 nozzle, *b'*, said casing, *b'*, having the air inlet opening, *b*, but it will be noted that the Bunsen device of Fig. 4 embodies the same elements and operates in the same way as the corresponding device of Fig. 1.

85 From the foregoing description it is to be observed that the generator *C*, or *C'* is directly in the path of the flame of the gases issuing from the mixing chamber, *A*, and the diaphragm, *G*, so that the generator is exposed to the intense heat of the burner for the purpose of securing an instantaneous conversion of the liquid into steam, and, further, of superheating the steam so that it will be supplied in a dry hot condition to the 90 injector nozzle, *D*, *D'*. The injector tube, *E*, extends into the mixing chamber, *A*, and discharges the mixture of steam and air at a point some distance in front of the port or opening between the Bunsen device and the 100 mixing chamber, whereby the injector tube prevents the mixture of steam and air from passing upwardly into the bunsen, and the pressure of the steam and air entrains a mixture of gas and air into the mixing chamber, 105 the two vapors being mixed in said chamber and ignited at the diaphragm, *G*.

110 It will be seen that in the construction described the force of the fuel jet in the bunsen is the means of entraining the air so that the apparatus may be started by simply lighting the gaseous mixture thus produced, and that the flame from the burner serves to vaporize the water which then starts the additional air supplied by means of a jet of 115 steam, and that thereafter the steam generated is superheated. It will also be seen that the superheater is a part of the burner itself and not a part of a fixed boiler. Further it will be seen that while the apparatus constructed as described may be used in some instances in connection with a fixed apparatus, it is especially adapted for use as a portable burner in which the superheated steam is generated from a supply of water 120 fed through a flexible connection, the gas also to be fed through a flexible connection thus adapting the portable apparatus for use in connection with flat irons, soldering irons, etc.

Having thus fully described the invention, what I claim as new, and desire to secure by Letters Patent is:

1. In an apparatus of the class described, 5 means for entraining air by a jet under pressure of a fixed gaseous fuel, means forming a part of the apparatus for generating and superheating steam, means for entraining air by a jet of the superheated steam, and 10 means whereby the steam and air are combined with the fuel mixture.
2. A portable burner provided with means for producing a mixture of air and a fixed gaseous fuel, a generator and superheater, a 15 nozzle communicating with said generator and superheater and arranged as described to entrain air by a jet of superheated steam, and flexible connections for supplying gas and water to the burner.
- 20 3. In a portable apparatus of the character described, the combination of a bunsen for mixing air and a combustible fixed gas by the action of a jet of the latter, a steam generator and superheater arranged to be heated by the burning gases of the apparatus, and means for injecting air into the said mixture by a jet of the superheated steam thus produced.
- 25 4. The combination in a burner, of a casing containing a mixing chamber and provided with air inlets, a bunsen for mixing air and a combustible fixed gas by the action of a jet of the latter the casing of which communicates with said chamber, a steam generator and superheater carried by and adjacent to the casing and arranged to be heated by ignited gases passing from said casing, and a steam nozzle communicating
- 30 with the superheater and arranged adjacent to the air inlets to entrain air and inject it 40 into said chamber.
- 35 5. The combination of a casing containing a mixing chamber and provided with air inlets, a bunsen having a casing connected at an angle with the aforesaid casing, a 45 nozzle for injecting a fixed gas under pressure into the Bunsen casing, a nozzle at the rear of the mixing chamber adjacent to the air inlets, a generator and superheater adjacent to the casing containing the mixing 50 chamber, and means for supplying said last mentioned nozzle with superheated steam from the generator and superheater, the superheater and generator arranged to be heated by the flame of the mixed gases passing from the mixing chamber.
- 40 6. The combination in an apparatus of the character described, of a casing containing a mixing chamber, a mixing tube extending into said casing and provided with air inlets, a nozzle adjacent to the outer end of said tube, a steam generator and superheater communicating with said nozzle and arranged to be heated by the flame of mixed 55 gases passing from said chamber, and a bunsen having a casing communicating with said chamber, and a nozzle for injecting a jet of fixed gases under pressure into the bunsen.

In testimony whereof I have signed my name to this specification in the presence of two subscribing witnesses.

HANS E. GRABAU.
